CLAIM

The ornamental design for a therapeutic ice bath apparatus as shown and described.

DESCRIPTION

FIG. 1 is a front perspective view of a therapeutic ice bath apparatus showing a new design with a lid engaged; FIG. 2 is another front perspective view thereof with the lid disengaged;

FIG. 3 is a top view of FIG. 1;

FIG. 4 is a front view thereof;

FIG. 5 is a left view thereof;

FIG. 6 is back view thereof;

FIG. 7 is a right view thereof; and,

FIG. 8 is a bottom view thereof.

The broken lines in the drawing figures show portions of the therapeutic ice bath apparatus which form no part of the claimed design.
